UNITED STATES PATENT OFFICE.

OZRO NEWCOME WISWELL, OF LYNN, MASSACHUSETTS, ASSIGNOR TO THE GENERAL ELECTRIC COMPANY, OF NEW YORK.

ELECTRIC-ARC LAMP.

SPECIFICATION forming part of Letters Patent No. 662,995, dated December 4, 1900.

Application filed May 4, 1899. Serial No. 715,508. (No model.)

To all whom it may concern:

Be it known that I, OZRO NEWCOME WISWELL, a citizen of the United States, residing at Lynn, in the county of Essex and State of Massachusetts, have invented certain new and useful Improvements in Arc-Lamps, of which the following is a specification.

In electric-arc lamps of certain well-known types it has long been thought necessary to 10 arrange the magnets in such manner that they would give a constant pull over a wide range of movement. To attain this end, pole-pieces having paraboloidal tips have been used in connection with armatures having holes there- 15 in for the reception of the pole-tips.

In double-carbon lamps of the above types the voltage across the arc of the second pair of carbons is always higher than the voltage across the arc of the first pair of carbons. 20 This is due chiefly to the fact that the load on the adjusting-spring or its equivalent is decreased by an amount corresponding to the weight of the carbon consumed on the first rod, and consequently the carbons are slightly 25 more separated than in the first instance.

I have discovered that it is not advisable in the types of lamp above referred to to make the magnets exert a constant pull on their armatures over their entire range, but instead that 30 they should exert a sharp increase in pull at or about the clutch-tripping point. By placing a small ring of steel or iron, preferably the former, around the base of the paraboloidal tip I am enabled to operate a Thomson- 35 Houston double-carbon lamp in such manner that the voltage of both rods is practically identical. This is an important feature when the addition of several volts for each lamp supplied from a station is taken into consider- 40 ation, and, further, the saving in operation usually comes after midnight, when the additional light is unnecessary.

Referring to the accompanying drawings, which show an embodiment of my invention, 45 Figure 1 is a front elevation of a lamp, and Fig. 2 is a perspective view of a ring.

In the drawings, A and B represent electromagnets having cores G with paraboloidal pole-tips G', and mounted for movement with 50 respect thereto is an armature C, having holes therein through which the pole-tips can pass.

The poles are connected at the bottom by a yoke D and at the top by a non-magnetic clamp E. Situated just above the clamp on each pole-piece is a detachable ring F, made 55 of iron or steel, as desired, which ring may or may not be split. It is preferable to make the ring out of steel on account of the additional elasticity.

The cores G are commonly made from 60 wrought iron or steel rods, and for that reason it is preferable to employ rings which can be slipped over the pole-tips rather than to cut the cores with a projection out of solid stock, as it would involve a good deal of la- 65 bor, besides costing more for material. The rings can readily be made in a machine and can be applied to the lamp without disturbing any portion of the lamp mechanism.

The armature C is pivoted at any suitable 70 point, and an adjusting-spring H is employed to return it to the position shown. This armature controls the action of the carbon-rods I and I' through suitable clutches. When the carbon carried by rod I is consumed, the 75 second rod, with its carbon, is brought into action by suitable mechanism. (Not shown.)

The carbon-rod I feeds when the armature moves downward to a point about five-sixteenths of an inch from the clamp E, and the 80 rod I' feeds when the armature moves to a point about one-fourth of an inch from the clamp.

At the present time there is a large number of these lamps in daily operation, and I 85 can utilize my invention in connection with these lamps by providing a pair of spring-rings for each lamp, which rings can be sprung over the pole-tip and will remain, due to their gripping action. I have found by actual test 90 that closer regulation of both carbons can be obtained with my invention than without and that the second carbon will burn at the same voltage as the first with no rise in voltage.

Having thus described my invention, what 95 I claim, and desire to secure by Letters Patent, is—

1. In an electric-arc lamp, the combination of a feed-regulating magnet provided with a core and armature, one of which is permanently fixed and the other movable, the two having coöperating faces shaped to produce 100

a sudden decrease of the magnetic reluctance of the circuit and thereby afford a sharp increase of pull at or near the feeding-point of the lamp.

5. 2. In an electric-arc lamp, the combination of a feed-regulating magnet having a paraboloidal pole-tip, and an armature surrounding the pole-tip, the pole-tip being provided with an enlargement of magnetic material at 10 or near the feeding-point for exerting a sharp increase of pull.
3. In an electric-arc lamp, the combination of a core having a paraboloidal pole-tip, a winding therefor, an armature containing a 15 hole for the reception of the pole-piece, and

a ring of magnetic material for modifying the action of said pole-piece.

4. In an electric-arc lamp, the combination of a pair of magnets, each magnet having a core with a paraboloidal pole-tip, means for holding the cores in alinement, a moving armature, and a split magnetizable ring located between the armature and the said means for modifying the action of the pole-pieces. 20

In witness whereof I have hereunto set my 25 hand this 26th day of April, 1899.

OZRO NEWCOME WISWELL.
